UNITED STATES PATENT OFFICE.

ISAIAH L. ROBERTS, OF BROOKLYN, NEW YORK.

CARBONIZING APPARATUS.

SPECIFICATION forming part of Letters Patent No. 511,459, dated December 26, 1893.

Application filed December 8, 1892. Serial No. 454,541. (No model.)

To all whom it may concern:

Be it known that I, ISAIAH L. ROBERTS, a citizen of the United States, residing in Brooklyn, county of Kings, in the State of New York, 5 have invented a new and useful Electric Process and Apparatus for Baking Carbons; and I do hereby declare that the following is a full, clear, and exact description of the invention, which will enable others skilled in the art to 10 which it appertains to construct and use the same.

Heretofore carbons have been pressed in molds or dies, and placed in an oven or furnace and slowly heated for many hours and 15 even days, in order to completely decompose and carbonize the binding material. In this practice much time and fuel are lost, while the metallic boxes or other receptacles in which carbonization takes place, are rapidly oxidized 20 or in case of earthenware, soon broken.

The object of my invention is to apply heat electrically to the carbon in such a manner that the wear on the apparatus will be lessened, fuel saved and the time shortened in 25 carbonizing the binder. In order to accomplish this, I construct an apparatus shown in Figures 1, 2 and 3.

Fig. 1 is a plan partly cross-section of the apparatus when in operation. A and B are 30 the two parts of an iron clamp. B slides on the lower portion of A, and is moved back and forth by the lever L and held in place when tightened by the movable wedge M, which rests against the stop N. C and D are 35 fire clay slabs made fast to their respective jaws of said clamps by counter-sunken bolts *a a a a*. These fire clay slabs are faced with heavy asbestos *h h*, the whole being wide enough to take in the iron box, Fig. 3 and close 40 tightly against its sides and bottom.

Fig. 3 shows a vertical cross section of an iron box preferably perforated on its sides and bottom H H and closed at the ends by heavy masses of iron O O. These bars or 45 masses of iron are tipped with copper connectors S S brazed on at P²P². P P are couplers for connecting the conductors S S. The sides and bottom of the box are made of thin sheet iron, though other metals which will 50 stand a high heat may be used. The sheet iron should be made fast to the massive ends by being welded, cast or screwed on with small

screws near together as possible, so as to cause or secure as good contact as possible as at T T, Fig. 2. This box should have a partition, 55 if a large number of carbons are to be baked at once, or many partitions may be used. They should be of the same or near the same electrical resistance as the sides and bottom, for equal surface and cross-section. The partition is shown at J, Figs. 1 and 3. I I in all the figures are carbons. K K is sand filled in around the carbons to prevent air reaching them while hot.

To operate my process and apparatus I proceed as follows: I take as many carbon articles pressed or molded in the usual and well known way, electric arc light pencils for instance, and stand them on end in a single row on each side of the partition J, Figs. 1 and 3, 70 leaving a small space between each other and the partition and walls of the box. I now fill the spaces so left with sand, coarse enough not to fall through the perforations. I make the said box high enough to permit of covering 75 said carbons about two inches. I then place the box and carbons in between the jaws of the aforesaid clamping device, and force them together and lock them. The heavy masses of iron O O and copper connectors S S project out between the inclosing jaws, but the asbestos facings *h h* of the fire clay slabs cover the perforated sides completely. I then attach the connectors P P to a source of electricity of sufficient strength 80 to heat the thin sides, bottom and partition to a white heat. I prefer to apply the current slowly so as to drive off the gases which are liberated at a low temperature first and gradually raise it, until the box and contents 85 are white hot. If the heat is too suddenly raised the carbons will be porous and soft. When allowed to cool until danger of oxidation is passed, the box may be removed and another substituted. The conductivity of the 90 end masses of iron should be a great many times greater of cross section than the total metal in the sides, bottom and partition, so that they will not become so hot and waste the current. The use of the partition is to get a 100 uniform heat on both sides of the carbon which will prevent them from bending from unequal contraction when carbonizing.

The box is perforated for the purpose of

allowing the reducing hydro-carbon gases to escape outside and unite with any oxygen present next to the asbestos, and thus protect the box from destruction at such high temperatures as are used.

The object of the use of asbestos is to fit closely to the sides of the box and to insulate the heat thus causing it to remain next to the box. I use fire clay slabs also because they are firm and at the same time conduct the heat poorly. The sand in the box is used for the purpose of preventing the carbons from sticking to each other or the box while carbonizing; also to prevent air from getting to the hot carbons and for holding them firmly in position while carbonizing the binder and being porous will allow the gases to escape freely.

Having described my invention, what I desire to secure by Letters Patent is—

1. The process of charring or carbonizing which consists in placing the articles to be charred or carbonized in a non-conducting mass of material, such as sand or its equiva-

lent, then passing a current of electricity 25 through a conductor in contact with said mass.

2. An apparatus for charring or carbonizing by the heat of the electric current, which consists of a vessel that is a conductor of electricity, said vessel being held by a clamp 30 faced with a flexible facing, such as asbestos.

3. The combination of a perforated electrically conductive vessel and an outer non-conducting covering.

4. A box or vessel for containing substances 35 to be carbonized which has one or more conducting diaphragms through it, in the manner and for the purpose described.

5. A box or vessel which is a conductor of electricity, and which has comparatively massive ends, which ends are fastened thereto; 40 in the manner and for the purpose described.

In testimony whereof I affix my signature in presence of two witnesses.

ISAIAH L. ROBERTS.
